UNITED STATES PATENT OFFICE.

ESTELLE J. HODGES AND CARRIE R. MATHEWS, OF WINDER, GEORGIA.

GARMENT-DRAFTING PATTERN.

SPECIFICATION forming part of Letters Patent No. 540,985, dated June 11, 1895.

Application filed November 7, 1894. Serial No. 528,146. (No model.)

To all whom it may concern:

Be it known that we, ESTELLE J. HODGES and CARRIE R. MATHEWS, citizens of the United States, residing at Winder, in the 5 county of Jackson and State of Georgia, have invented certain new and useful Improvements in Adjustable Patterns; and we do hereby declare the following to be a full, clear, and exact description of the invention, such 10 as will enable others skilled in the art to which it appertains to make and use the same.

Our invention relates to adjustable patterns for drafting dresses or other garments, and it consists essentially of a skeleton pattern 15 made of ribs of flexible material of the width of the seam and so arranged as to be adapted for cutting along the outer edge, and for marking the material for sewing along the inner edge.

Our invention also consists of certain novel 20 features of construction and arrangement of parts hereinafter described and claimed.

Reference is had to the accompanying drawings, in which the same parts are indicated 25 by the same letters throughout the several views.

Figure 1 represents a plan view of the pattern arranged for the front of a dress-body. Fig. 2 represents a plan view of the adjustable 30 pattern for the front side body. Fig. 3 represents a plan view of the adjustable pattern for the back side body. Fig. 4 represents a plan view of the adjustable pattern for the back of the dress-body, and Fig. 5 represents 35 a plan view of the adjustable pattern adapted for use in cutting out both the top and the bottom of the sleeves.

The various figures represent a complete 40 pattern for cutting out a dress waist for women, or a body for children; but the same idea is readily applicable to cutting out garments of various descriptions.

In the device shown in Fig. 1 a and a' represent two strips of rib steel, brass, tin, or 45 pasteboard which are adjustably connected to each other by a sliding clip s and the two parts represent the front measure of the body, the upper part being graduated to represent inches, and the lower part being slid down 50 to the desired distance which is indicated by the figure corresponding to the ordinary front measure. To the upper strip a' , the curved

neck piece b is pivoted as at p , and below this neck piece the chest piece c is also pivotally connected, while to the lower piece a , 55 the waist piece d is pivoted.

In all the various figures p represents a pivot, preferably an eyelet, and s represents a sliding clip and s' the combination of two revoluble clips connected back to back. 60

The shoulder piece e is connected to the neck piece b by the sliding clip s , and to the arm's-eye f by the double clip s' , and thus it may be slid up and down the neck piece and up and down the arm's-eye piece to the corresponding marks which are graduated on each. The chest piece c is connected to the arm's-eye piece by the clip s' through which the said chest piece is free to slide.

The arm's-eye piece f is pivotally connected 70 to the upper piece g' of the under arm piece which is graduated as shown, and is connected by sliding clips to the lower portion thereof g . This portion is curved outward as at g^2 and slides along the waist piece d being 75 held thereon by the sliding clip.

The upper portion of the waist piece is graduated for women, and the lower portion thereof is graduated for children, and is marked "children's scale." 80

The scales on the various parts are so regulated that the sum of the scales on any one part will equal the total measure of the said part; or in other words each difference of scale represents a difference proportional 85 to the change in the measure corresponding thereto.

It will be seen by examining the front piece, which is formed of the two adjustable parts a and a' , which are curved outward as at a^2 , 90 that when the measure is long the outer edge will represent the sum of the two curvatures, and will thus allow for a prominent bust, while when the measure is short, the front piece will approximate more closely to a straight line which is the desired condition of children's patterns.

The waist piece d has pivoted thereto, but sliding thereon a dart h which is provided with a curved tip h' and a plurality of holes, 100 preferably spaced a half inch apart, and indicated by h^2 . In order to cut out the dart, mark through the eyelet hole that corresponds most nearly to the dart measure, and then

swing the point of the dart h' to one side and mark along the outer edge of the dart on the material the line such as is indicated by the dotted line h^4 . Then swing the dart in the 5 opposite direction about its pivot and mark the line h^5 on the material along the opposite side of the dart piece h . To cut out the second dart, slide the dart piece along the waist piece to the proper position and cut out a dart 10 a half inch higher but in the same way.

In using the hereinbefore described pattern trace on the inside for sewing and on the outside for cutting except with the neck and arm's-eye, where the cutting should be on the 15 inside.

By having the various strips about three-fourths of an inch wide, or the most common width of a seam, it is possible to use the same pattern for marking both the cutting 20 edge and the sewing edge.

In the adjustable pattern shown in Fig. 2 for the front side body, the two parts k and k' are adjustably connected together by sliding clips while to the top of the upper piece k' 25 the arm's-eye piece f^2 is pivoted. The waist piece d^2 is pivoted to the lower piece k and these two pieces f^2 and d^2 slide through clips on the adjustable pieces m and m' . It will be thus seen that the pattern may be readily 30 adjusted to the various measurements of the front side body. In a similar way, in the structure shown in Fig. 3, the curved strips q and q' are connected together by sliding clips and have pivoted thereto the arm's eye 35 piece f^3 and the waist piece d^3 , which two latter pieces pass through the clips s pivoted to the pieces r' and r , respectively, which are secured together by sliding clips. These parts 40 r and r' are curved as shown at r^2 and the lower part r is curved as at r^3 .

The back pattern shown in Fig. 4, consists of two back pieces t and t' adjustably connected together and having pivoted thereto the curved neck piece b' , the back width c' 45 and the waist piece d' . The lower part of the back piece t is bent inward at an angle just above the waist piece.

The curved under arm pieces u and u' are adjustably connected together and the lower 50 piece u is also adjustably connected to the waist piece d' , while the upper piece u' has pivoted thereto the curved arm's eye piece f' . The back width c' and the shoulder piece e' are attached to the curved arm's eye piece by 55 double clips s' ; while the said shoulder piece is connected to the curved neck piece b' by a sliding clip s .

The device shown in Fig. 5 represents a combination pattern for both the top and the 60 bottom of the sleeve, when the parts are in the position shown in full lines, the pattern is adapted for use in drafting the top of the sleeve. The single curved side pieces w and y are connected by the curved top sleeve 65 piece x which is slid to the same figure in each of the clips s' and s^2 . The clip s^2 is com-

posed of three parts each revolvably connected to the other. The wrist piece z is separated by a line z' into a top scale used for measuring the top of the sleeve, and a bottom scale 70 used for measuring the bottom of the sleeve at the wrist. When the bottom of the sleeve is being cut out the lower portion of the piece v is slid on to the bottom scale on the piece z , the top of sleeve piece x is swung out into the 75 position shown in dotted lines, and the oppositely curved bottom of the sleeve piece y is swung up into the position shown in dotted lines and passed into the clip s' , the piece x having been previously withdrawn from the 80 said clip. The longitudinal measurements on the sleeve are indicated by the graduations shown on the pieces v and w . Thus it will be seen that the same pattern is adapted 85 for use in cutting out both the top and the bottom of the sleeve.

In adjusting the various patterns be careful that each line crosses at the proper figure according to the measures. Trace on the inside for sewing, and on the outside for cutting, 90 except on the neck and arm's-eye, which two should be cut on the inside.

It will be noted that most of the cutting edges are perfectly free from obstructions to the drafting pencil, and the pattern may be 95 simply laid on the cloth and cut around with the shears if it is preferred.

The herein described device has a wide range of adaptability being suited for almost any size of woman or child. It will be obvious that the same principle might be applied to the construction of patterns for various other garments. 100

It will be seen that the herein described device comprises a complete pattern for the 105 body of a dress or similar garment, and that each of the parts of the pattern may be readily adjusted to fit in with the various other parts of the pattern.

Having thus described our invention, what 110 we claim, and desire to secure by Letters Patent of the United States, is—

1. An adjustable pattern for drafting the fronts of garments comprising in combination, the outline pieces, to wit, the front, 115 under arm, neck, shoulder, and arm's eye pieces, adjustably and pivotally connected together, the chest piece adjustably connecting the front and arm's-eye pieces, the waist piece adjustably connecting the front and under arm pieces, and the dart piece pivoted on the 120 waist piece, and adapted to slide thereon, said dart piece comprising an approximately rectangular lower portion and a tapering upper portion, the said upper portion being provided 125 with a plurality of holes arranged at graded distances from the pivot of said dart, substantially as and for the purposes described.

2. An adjustable pattern for drafting the sleeves of garments, comprising in combination, the front and back curved sleeve pieces, 130 the wrist piece adjustably connected to the

front and back sleeve pieces, and the curved top sleeve piece adjustably connected to both of said front and back sleeve pieces, and the curved bottom sleeve piece adjustably connected to the back sleeve piece at the intersection of the top and back sleeve pieces, substantially as described.

In testimony whereof we affix our signatures in presence of two witnesses.

ESTELLE J. HODGES.
CARRIE R. MATHEWS.
